UNITED STATES PATENT OFFICE.

PAUL RASCHE, OF U-BARMEN, GERMANY, ASSIGNOR TO FRIEDRICH KLEWINGHAUS,
OF BARMEN, GERMANY.

BRAIDING MACHINE.

Application filed March 25, 1922. Serial No. 546,905.

To all whom it may concern:

Be it known that I, PAUL RASCHE, a citizen of the German Republic, and residing at U-Barmen, Germany, have invented certain new and useful Improvements in Braiding Machines, of which the following is a specification.

This invention relates to an improved braiding-machine, which, above the known art, has the advantage of easy and cheap manufacture and great simplicity.

The accompanying drawing shows the improved braiding-machine: Fig. 1 is a cross-section on the line A—B of Fig. 2, which is a fragmentary plan view of the same, partly in section on the line C—D of Fig. 1, while Fig. 3 is a perspective view of one of the segments of which the race-plate for the bobbins is composed.

On a base plate *a*, the stationary axles *b* with the rotary bosses *c* are arranged in circular fashion in a way known in the art, said bosses carrying below the spur-wheels *d*, which are in gear with each other, and above the horn-gears *e*, which are provided with radial notches *f*, adapted to engage the bobbin foot *g* between them and to drive the same along during their rotation, the base *h* of the bobbin being guided in the upper race-plate of the machine.

According to the invention, said upper race-plate is formed or composed of a plurality of separate detachable segments *i*, *k*, *l*, *m*, and so on, of annealed cast-iron, which form the race for the bobbins and which are of similar formation and so designed and mounted that they form each two tangential grooved semicircles *n* concentric with said axles or bosses, the tangential point of said grooved semicircles lying at the middle of each segment and being the crossing-point of each two adjacent circular race portions whereby a continuous race is formed, the attachment of said race segments to the base-plate *a* being effected by means of distance-bolts *o*, *p*.

The improved race-plate thus formed of the separate segments above-described is mounted below the horn-gears *e*, so that the base *h* of the bobbin running in the grooves *s* of the race-plate is also located beneath the bobbin foot *g*, which is provided with boundary flanges *q* embracing the horn-gears *e* and located beyond the race-plate.

Around each boss *c*, a free space *r* is left

by the formation of said segments for the bobbin drivers.

A connection between the several segments is not required, a small gap *t* being left between the adjacent lateral portions of each two segments, the manufacture and mounting of the annealed cast-iron segments being thus rather cheap, while each segment can be easily and quickly interchanged in case of need.

What I claim is:—

1. In a braiding-machine, in combination, a base-plate, stationary axles arranged in circular fashion on the latter, rotary bosses on said axles, spur-wheels—one at the lower end of each boss—in gear with each other, horn-gears at the upper ends of said bosses, a fixed race-plate arranged between said spur-wheels and horn-gears and consisting of a plurality of separate similar segments of annealed cast-iron forming a continuous race of circular race portions and located to leave a free space around each boss and a small gap between their adjacent lateral portions, and distance-bolts to detachably attach said segments to said base-plate, substantially as and for the purpose set forth.

2. In a braiding-machine, in combination, a base-plate, stationary axles arranged in circular fashion on the latter, rotary bosses on said axles, spur-wheels—one at the lower end of each boss—in gear with each other, horn-gears at the upper ends of said bosses, a fixed race-plate arranged between said spur-wheels and horn-gears and consisting of a plurality of separate similar segments of annealed cast-iron forming a continuous race of circular race portions and located to leave a free space around each boss and a small gap between their adjacent lateral portions, and distance-bolts to detachably attach said segments to said base-plate, each segment being formed of two tangential grooved semi-circles concentric with said axles and bosses and the tangential point of said semicircles lying at the middle of each segment and being the crossing-point of each two adjacent circular race portions, substantially as and for the purpose set forth.

3. In a braiding-machine, in combination, a base-plate, stationary axles arranged in circular fashion on the latter, rotary bosses on said axles, spur-wheels—one at the lower end of each boss—in gear with each other, horn-gears at the upper ends of said bosses,

a fixed race-plate arranged between said spur-wheels and horn-gears and consisting of a plurality of separate similar segments of annealed cast-iron forming a continuous race of circular race portions and located to leave a free space around each boss and a small gap between their adjacent lateral portions, distance-bolts to detachably attach said segments to said base-plate, a bobbin foot engaged by said horn-gears, and a bobbin base guided in said race-plate, substantially as and for the purpose set forth.

4. In a braiding-machine, in combination, a base-plate, stationary axles arranged in circular fashion on the latter, rotary bosses on said axles, spur-wheels—one at the lower end of each boss—in gear with each other, horn-gears at the upper ends of said bosses, a fixed race-plate arranged between said spur-wheels and horn-gears and consisting

of a plurality of separate similar segments of annealed cast-iron forming a continuous race of circular race portions and located to leave a free space around each boss and a small gap between their adjacent lateral portions, distance-bolts to detachably attach said segments to said base-plate, a bobbin base guided in said race-plate, a bobbin foot engaged by said horn-gears, and boundary flanges on said bobbin foot located beyond said race-plate and embracing said horn-gears, substantially as and for the purpose set forth.

In testimony whereof I have hereunto set my hand in the presence of two subscribing witnesses.

PAUL RASCHE.
